UNITED STATES PATENT OFFICE

PERCY W. VALENTINE, OF NATICK, MASSACHUSETTS

RIBBED INNER SOLE

Application filed February 6, 1929. Serial No. 337,817.

This invention relates to innersoles of the type used in making welt shoes, such soles having a rib on one face, extending in a line generally similar to the edge of the sole, for receiving the stitches of the inseam by which the upper and welt are secured to the innersole. More particularly it relates to those innersoles of the type above indicated of which the rib is an originally separate strip of material attached to the body of the sole. My object has been to simplify and reduce the cost of making such ribbed innersoles by enabling a rib having sufficient strength and stiffness to be made out of a single strip of textile fabric, without an additional or inserted reinforcing means; which rib, further, may be folded or laid down and left in that position during all stages in the handling and treatment of the innersole up to the inseaming step when it is sewed to the upper and welt. Another part of my object has been to provide a fabric rib with attaching flanges at both sides of the base of the rib, but without any raw or cut edge permitting the interwoven strands to ravel out on the attaching flange which is directed outward toward the edges of the innersole.

The invention consists in the novel features described in the following specification and shown in the drawing furnished herewith, and pointed out in the appended claims.

In the drawing,—

Fig. 1 is a bottom plan view of an innersole embodying the present invention;

Fig. 2 is a detail sectional view on a larger scale taken on line 2—2 of Fig. 1;

Fig. 3 is a view similar to Fig. 2 showing a slight modification in the arrangement of the parts of the fabric strip which forms the rib and its base flanges.

In the present invention the innersole, following a long accepted and widely used practice, is made of a body *a* of leather, leather-board or any other suitable material, and a rib *b* made of a folded strip of textile fabric laid in the desired outline on one face of the innersole body and fastened thereto by sewed seams. The novelty of the invention consists mainly in the characteristics of the rib.

In making the rib I take a strip of suitably

strong and heavy textile fabric, preferably cotton duck of substantially the weight and texture ordinarily used for the ribs of innersoles of this general class. The strip is cut on the bias with sufficient width to provide the rib proper and base flanges hereinafter described. It is bent double on the longitudinal fold *c*, and the parts or plies *d* and *e* on each side of the fold are brought together forming a two-ply rib. The two plies of the material are bent on folds *f* and *g* oppositely to one another and outwardly from the base portion of the rib; and the part which is thus bent outward on the fold *g* is doubled back on a fold *h* and brought under the part which is bent back on the fold *g*. Thus the zones adjacent to the two edges of the strip are superposed one on the other and form a two-ply flange *k*, while the part folded at *h* forms a two-ply lip *l*. The edges of the plies forming the flange *k* may be in alignment with each other, as shown in Figs. 1 and 2, or the margin of the upper ply of the flange *k* may overlap the edge of the lower ply as shown in Fig. 3. The rib with its flanges thus formed is laid on the surface of the innersole body following generally the outline thereof, with the flange *l* directed outward toward the edges of the body, and is attached by three stitched seams *m*, *n* and *o*, one of which passes through the flange *l* and the other two through the flange *k*.

Preferably a viscous fluid adhesive or size is applied to the strip immediately prior to folding, being applied to the surface which provides the inside surfaces, within the folds, when the strip is folded as above described. Preferably the adhesive substance is so applied only to so much of the strip as provides the plies *d* and *e* of the rib proper for the purpose of stiffening the rib proper and preventing separation from one another of the plies thereof. But it may be applied over the whole surface of the strip if desired to reinforce and stiffen also the attaching flanges. The sizing or adhesive material is preferably of such consistency that it penetrates only partially into the fibers of the component yarns of the fabric without wholly saturating the fabric. The presence

of the adhesive is indicated by lines of shading in and between the plies *d* and *e*.

The steps of coating and folding the fabric are performed in such close sequence that the coated plies are brought together before the coating material has dried or set. Any cement, glue or other adhesive or sizing composition which has the desired adhesive or stiffening qualities may be used for this purpose.

Preferably also the further step of stitching the rib to the innersole body is carried out in continuation of the folding step; the strip passing directly from a progressively acting folder to the innersole body while the latter is being fed past the needles of a plural needle sewing machine, so that all the attaching seams are stitched at the same time.

While the sizing compound is still soft, the rib is preferably laid down away from the edges of the sole, as shown in the sectional views. This opens wide the angle between the rib and the flange of the sole, facilitating the application of cement in this angle when cement is used preparatory to pulling over the upper in lasting. The outer flange or lip is an advantage in this connection in that the stitches which pass through it, in being set tight, force the rib inward, placing it in the necessary position so that, when the sole has been molded, it may be easily raised by the pick up of the guide finger of the inseam stitching machine.

The inside flange, being double, gives additional strength to withstand the strain of sewing the inseam, hence preventing the rib from being stretched outward during the inseaming operation which, if it were allowed to occur, would cause loss of the desired shape of the lasted shoe. Separate ribs which are attached by means of flanges of single thickness are liable to stretch and make the shoes defective. Furthermore, the mode of folding the rib enables the application of sizing substance, when used, to be placed only within the fold which forms the rib proper and enables those parts which are penetrated by the needles of the sewing machine to be entirely clear of size, thus avoiding smearing and gumming up of the needles with the sticky sizing substance. The inclusion of this substance within the rib also protects the folder from being smeared and gummed up with the size.

What I claim and desire to secure by Letters Patent is:

1. An innersole comprising a sole body and an attached rib formed of a strip of textile fabric folded double longitudinally to make the rib proper, the plies folded by such fold being then bent outward oppositely to one another at the base of the rib proper, and one of said plies being doubled back and extended under the other ply.

2. In an innersole a separately attached

rib formed of a folded strip of material having a longitudinal fold providing a rib proper, and a second longitudinal fold providing an attaching flange at the base of the rib proper, and the opposite edge portions of the strip being superposed one upon the other and providing a base flange extending to the opposite side of the rib proper from the first named flange.

3. In an innersole a separately attached rib formed of a folded strip of material having a longitudinal fold providing a rib proper, a second longitudinal fold providing an attaching flange at the base of the rib proper, and the opposite edge portions of the strip being superposed one upon the other and providing a base flange extending to the opposite side of the rib proper from the first named flange, and adhesive or sizing material within the fold forming the rib proper.

In testimony whereof I have affixed my signature.

PERCY W. VALENTINE.
